(57) **CLAIM**

We claim the ornamental design for a hatchet, as shown and described.

DESCRIPTION

FIG. 1 is a front top perspective view of the claimed design according to one embodiment;

FIG. 2 is a left side view of the claimed design of FIG. 1;

FIG. 3 is a right side view of the claimed design of FIG. 1;

FIG. 4 is a front view of the claimed design of FIG. 1;

FIG. 5 is a rear view of the claimed design of FIG. 1;

FIG. 6 is a top view of the claimed design of FIG. 1;

FIG. 7 is a bottom view of the claimed design of FIG. 1;

FIG. 8 is a rear top perspective view of the claimed design of FIG. 1;

FIG. 9 is a front top perspective view of the claimed design according to another embodiment;

FIG. 10 is a left side view of the claimed design of FIG. 9;

FIG. 11 is a right side view of the claimed design of FIG. 9;

FIG. 12 is a front view of the claimed design of FIG. 9;

FIG. 13 is a rear view of the claimed design of FIG. 9;

FIG. 14 is a top view of the claimed design of FIG. 9;

FIG. 15 is a bottom view of the claimed design of FIG. 9; and,

FIG. 16 is a rear top perspective view of the claimed design of FIG. 9.

The broken lines in the drawings are for purposes of illustrating unclaimed portions of the design.

1 Claim, 8 Drawing Sheets
